UNITED STATES PATENT OFFICE.

ADOLF GYGER, OF RIVERSIDE, CALIFORNIA.

MECHANICAL DOLL.

Application filed October 5, 1927. Serial No. 224,116.

This invention relates to dolls and more particularly to mechanical dolls.

The primary object of this invention resides in the provision of a doll adapted to 5 toss a smaller doll from one hand to the other.

Another object of this invention resides in the provision of a doll adapted to toss a smaller doll from one hand to the other and simultaneously direct its face toward the 10 smaller doll as it alternately changes its position on opposite sides of the larger doll.

A further object of this invention resides in the provision of a doll associated with a smaller doll so as to change the relative positions of the same by mechanical means.

A still further object of this invention resides in the provision of a large doll and a smaller doll associated so as to transfer the smaller doll from one hand to the other 20 through the instrumentality of mechanical means which not only manipulate the arms and cause movement of the smaller doll, but cause the large doll to turn its face toward the smaller doll.

In addition to the aforesaid objects, this 25 invention resides in the provision of dolls adapted to change their relative positions by means which are manually or mechanically actuated.

With these and other objects in view, this 30 invention resides in certain novel features of construction, arrangement and combination of elements to be hereinafter set forth in the specification, illustrated in the accompanying drawings and pointed out in the appended 35 claim, and, while the disclosure depicts my present conception of the invention, the right is reserved to make such changes in construction as come within the scope of the 40 claim.

In the accompanying drawings forming a part of this application:

Fig. 1 is a front view of the associated dolls constructed in accordance with this invention, the same showing the smaller doll in full lines as supported by one hand of the larger doll and in dotted lines as supported by the other hand of the larger doll;

Fig. 2 is a rear view thereof;

Fig. 3 is a side view thereof;

Fig. 4 is a vertical, sectional view on line 4-4 of Fig. 1;

Fig. 5 is a horizontal, sectional view on line 5-5 of Fig. 1;

Fig. 6 is a diagrammatic view of a mechani-

cal operator for manipulating the arms of the larger doll to change the position of the smaller doll.

In the present embodiment of this invention, the numeral 5 designates a large doll 60 having arms 6 pivoted at the rear of its body for vertical movement and head 7 pivotally supported on a vertically disposed axis.

The arms 6 project inwardly toward one another from their pivots, herein designated 65 by the numeral 8, and are connected by a yoke 9 preferably formed of flexible cord or the like, which is preferably connected to a flexible cord 10 or the like whereby both arms will be simultaneously actuated by pulling 70 the flexible cord 10, and, while the first five illustrations of the invention disclose the cord 10 as utilized for manual manipulation of the arms, provision is disclosed in Fig. 6 75 whereby the arms and associated elements are manipulated by mechanical means capable of producing like results.

Journaled through the medial portion of the body of the large doll and above the horizontal plane occupied by the arms of the large 80 doll is a support 11 having an elongated portion 12, disposed in the path of the arms 6, and a shorter portion 13 disposed so as to manipulate the head of the large doll through the instrumentality of a right angularly bent 85 trunnion 14 forming a pivotal support therefor.

The free end of the elongated portion 12 of the support 11 is bent forwardly to provide a journal 15 adapted to pivotally support a small doll 16 which, when lodged in close association with either arm of the large doll, will present its entire configuration in front of the arm so as to appear as though it were grasped by the hands on the arms of 95 the large doll. This structure permits the small doll to assume the proper pose when transferred from one side of the large doll to the other and, through the provision of anchoring the small doll to the journal 15 100 with greater weight below the point of anchorage, it will always assume in its predetermined pose when transferred from one position to another.

It is apparent that by pulling the cord 10, 105 the arms 6 will assume a perpendicular position and that arm with which the small doll is associated will swing the elongated portion of the support 11 to the opposite side of its pivotal point so it will gravitate 110

on the opposite side when the arms return to their normal horizontal positions and, during the movement of the elongated portion of the support 11, the shorter portion thereof 5 engages the trunnion 14 to cause the head to turn on its vertical axis so the face of the larger doll is directed toward the small doll.

While the invention herein discloses dolls associated, it is to be understood that the embodiment may be arranged to simulate the movements of other objects and can readily be arranged to represent the movement of the legs.

With this invention fully set forth, it is 15 manifest that a doll is produced which is capable of simulating certain attractive motions of individuals and, through the mechanical means employed, the cost of manufacture will be reasonable.

20 Having thus described my invention, what

I claim and desire to protect by Letters Patent is:

The combination of a doll having pivoted arms, a head and a trunnion pivotally connecting the head to the body of the doll, a 25 smaller doll, a support including a trunnion for pivotally connecting the support to the large doll, said support pivotally connecting the smaller doll to the larger and disposing the smaller doll in the path of the arms of the larger doll, an offset portion on the trunnion of the support, an offset portion on the trunnion of the head, said offset portion being disposed in the path of the offset portion of the trunnion of the support and means connected to the arms whereby the arms and head 30 operate in unison.

35 In testimony whereof I affix my signature.

ADOLF GYGER.
